UNITED STATES PATENT OFFICE.

HENRY J. HEINZ, OF PITTSBURG, PENNSYLVANIA.

DESIGN FOR A PICKLE-BOTTLE.

SPECIFICATION forming part of Design No. 12,803, dated March 14, 1882.

Application filed January 27, 1882. Term of patent 14 years.

To all whom it may concern:

Be it known that I, HENRY J. HEINZ, of Pittsburgh, in the county of Allegheny and State of Pennsylvania, have invented a new and useful Improvement in Designs for Pickle-Bottles; and I do hereby declare the following to be a full, clear, and exact description thereof, reference being had to the accompanying drawings, forming a part of this specification, in which—

Figure 1 is a side view of a catchup-bottle made of my improved design. Fig. 2 is a like view of a modified form, and Fig. 3 is a like view of a mustard-bottle.

Like letters of reference indicate like parts in each.

My improved design consists of a bottle having a plain cylindrical middle section, *a*, bounded at the upper and lower edges by rings *b*. Both above and below the rings *b* is a tapered paneled section, *c* and *d*, the upper one terminating at the shoulder *e* and the lower

one at the flat bottom *f*. Above the shoulder *e* is a pear-shaped section, *g*, the stem of which constitutes the neck and mouth of the bottle. 25

This bottle is designed for use in bottling catchup and other condiments.

In the modified form of Fig. 2 the upper paneled section, *c*, is omitted, and a rounded section, *h*, is used. 30

My improved design has a handsome and appropriate appearance.

What I claim as my invention, and desire to secure by Letters Patent, is—

The design for condiment-bottle, herein described and shown. 35

In testimony whereof I have hereunto set my hand this 13th day of January, A. D. 1882.

HENRY J. HEINZ.
